A. V. DA COSTA

POWER PRESS

Filed August 31, 1922

Fig. 1

UNITED STATES PATENT OFFICE.

ARTHUR V. DA COSTA, OF PROVIDENCE, RHODE ISLAND, ASSIGNOR, BY MESNE ASSIGNMENTS, TO PROVIDENCE PRESS MACHINERY CO., INC., A CORPORATION OF RHODE ISLAND.

POWER PRESS.

Application filed August 31, 1922. Serial No. 585,409.

To all whom it may concern:

Be it known that I, ARTHUR V. DA COSTA, a citizen of the United States, residing at Providence, in the county of Providence and State of Rhode Island, have invented 5 certain new and useful Improvements in Power Presses, of which the following is a specification.

This invention relates to improvements 10 in the construction of fluid pressure operated power presses adapted more particularly for use by jewelers for stamping out small pieces in the manufacture of jewelry and the like, but this press may be used for 15 any other purpose for which it is adapted; and the object of this invention is to provide a press of this character which is simple, practical and inexpensive in construction, comprising a cylinder having a 20 piston operatively mounted therein and carrying a plunger member, adjustable means being provided for limiting the extent of the working stroke of the piston and plunger.

25 A further object of the invention is to provide adjustable means for limiting the operating stroke of the valve whereby the speed of movement of the piston is nicely controlled.

30 A still further object of the invention is to provide cushioning means for arresting the return stroke of the piston.

With these and other objects in view, the invention consists of certain novel features 35 of construction, as will be more fully described, and particularly pointed out in the appended claims.

In the accompanying drawings:

Figure 1 is a sectional front elevation of 40 the device.

Figure 2 is a side elevation of the device showing the supporting table partly in section.

Figure 3 is an end view of the valve showing 45 the adjustable means for controlling the extent of its opening and closing strokes.

With reference to the drawings, 10 designates a table on which the machine is mounted and 11 the legs for supporting the 50 table. The press comprises essentially a cylinder 12 in which is operatively mounted a piston 13, the same having a boss 14 which extends into a corresponding recess 15 in the upper end of the plunger member 16.

55 This plunger is secured to the piston by

means of screws 17, a space being left between the piston and the plunger for the reception of a leather packing 18. The plunger member is of a diameter smaller than that of the piston and the leather packing 60 18 fills the space about the outer end of the plunger and renders the piston tight against the lifting fluid pressure which enters through a port 19.

The lower end of the cylinder 12 is secured to a guide sleeve 20, which sleeve is supported on the standard 9 extending upward from the base 27 and through which sleeve 16 the plunger works and between this guide sleeve and the lower end of the 70 cylinder is left a recess 21 in which the leather packing 22 fits to prevent the fluid pressure from flowing downwardly between the sleeve and the plunger.

The lower end of this plunger is provided 75 with a recess 23 for the reception of the shank of a tool 24 which is secured in position by means of a binding screw 25, to cooperate with a die or other tool 26 which is supported on the base 27.

80 The upper portion of this plunger is provided with an elongated axially-disposed chamber 28 which is preferably formed square in cross section for the reception of a nut 29, a portion of which is also formed 85 square to fit loosely in said chamber so as to prevent it from rotating therein.

It is found in practice necessary to be 90 able to limit the extent of the downward stroke of this plunger, particularly when cutting tools are employed for cutting out the stock whereby the plunger will be arrested after the tool has passed through the work, and to accomplish this in a simple and effective way, I have provided an adjusting screw or threaded spindle 30, the lower end of which passes through the piston head and is threaded into the nut 29, while the upper end extends through the cylinder head 31 and is threaded for a short distance to receive the binding or locking member 32, and to the upper end of this spindle 95 is secured an operating wheel or handle 33.

A collar member 34 is formed on the spindle on the inside of the cylinder whereby 105 by loosening the binding member the spindle may be rotated by the wheel to adjust the nut 29 in its chamber, either up or down on the spindle, after which the binding nut 32 is rotated by its handle 35 to jam against the 110

head of the cylinder, to secure the spindle in adjusted position.

It is found in practice of advantage to provide a cushioning means for arresting the upward stroke of the piston, and, therefore, to accomplish this, I have mounted a disc 36 on the spindle 30 above the collar 34, of a diameter smaller than that of the cylinder, and I have provided a recess 37 in the head of the cylinder which is adapted to receive the plate 36, whereby when the piston is raised the air is trapped in this recess by this plate to easily arrest the upward stroke of the piston.

10 In order to control the movement of the piston and its plunger by air pressure, I have formed a channel 38 in the side wall of the cylinder and in this channel I have mounted a rotary valve 39 of the plug type, which is provided with a three-way port 40. A lever 41 is connected to the outer end of the valve which is operated from the foot pedal 42 through a connecting rod 43.

25 The fluid pressure, preferably compressed air, is admitted through the supply pipe 45 to enter directly to the chamber 46 formed between the packings 18 and 22, to constantly act upon the comparatively small area of the piston, to move it in an upward direction and when the valve 40 is in the position shown in Figure 1 the pressure above the piston is released to escape through an exhaust pipe 44 thus permitting the piston to rise after having performed an operating stroke.

35 When another operating stroke is desired the foot of the operator presses downwardly upon the lever 42 thus rotating the valve causing its ports to close the exhaust to pipe 44 and register with the pressure passageway leading to the inlet pipe 45, whereby the pressure on the greater area on the upper side of the piston immediately forces it down against the pressure on the smaller area in chamber 46 to perform a working stroke and when this foot lever is released the valve mechanism is returned to the position illustrated in Figure 1, by action of spring 52 to exhaust the pressure in the head 40 of the cylinder and permit the plunger to lift, ready for another working stroke.

45 In some instances it is found desirable to limit, either or both the opening and closing strokes of the valve so as to control the 55 volume of flowing pressure either into or out of the upper portion of the cylinder and so limit the traveling speed of the piston stroke either up or down, and to accomplish this in a simple and effective way, I have 60 formed a pair of ears 47 and 48 on this valve

through which I have tapped stop screws 49 and 50, which screws are adjustable endwise and are adapted to bring up against the surface 51 on the cylinder and by adjusting them endways the stroke of the valve may 65 be nicely controlled to open the passageway to the desired extent either for admitting or discharging pressure therethrough.

70 My improved power press is very simple and practical in its construction and effective in its operation and by its use work may be very rapidly operated upon, and the force of the blow nicely regulated.

75 The foregoing description is directed solely towards the construction illustrated, but I desire it to be understood that I reserve the privilege of resorting to all the mechanical changes to which the device is susceptible, the invention being defined and limited only by the terms of the appended claims. 80

I claim:

1. In a power press, a cylinder, a piston in said cylinder carrying a plunger member provided with an elongated chamber, a stop nut slidably but non-rotatably mounted in said chamber, a threaded spindle extending through said cylinder head and said piston into said nut, means whereby said spindle may be rotated to adjust said nut thereon to limit the outward stroke of the piston, and a valve for controlling the reciprocating action of said piston. 85

2. In a power press, a cylinder, a pressure-operated piston in said cylinder carrying a plunger member provided with an elongated chamber, a stop nut slidably but non-rotatably mounted in said chamber, an adjusting screw extending through said cylinder head and said piston into said nut, means whereby said screw may be rotated to adjust said nut thereon to limit the outward stroke of the piston, means for binding said screw in adjusted position, and a valve for controlling the reciprocating action of said piston. 95

3. In a power press, a cylinder having a piston operatively mounted therein and carrying a plunger member, a spindle extending through said cylinder into said piston, an adjustable stop member on said spindle for limiting the extent of the outward stroke of said piston, a valve for controlling the admission and discharge of pressure to and from the upper side of the piston, ports for admitting a constant pressure to return the piston after each working stroke, and means for cushioning the return stroke of the piston. 105

110 In testimony whereof I affix my signature.

ARTHUR V. DA COSTA.
